UNITED STATES PATENT OFFICE.

LOUIS COURTIAL, OF LYON, FRANCE.

FURNITURE.

1,249,721.

Specification of Letters Patent. Patented Dec. 11, 1917.

Application filed February 20, 1917. Serial No. 149,797.

To all whom it may concern:

Be it known that I, LOUIS COURTIAL, a citizen of the Republic of France, and resident of Lyon, France, 13 Rue Malesherbes, have invented a new and useful Improvement in Furniture, of which the following is a specification.

The present invention has for its object the provision of an article of furniture such as an upholstered chair, stool, couch, divan, or the like, in which the upholstery or coverings for the seat, back and arms may be quickly and easily removed and new upholstery or coverings substituted.

15 A practical embodiment of my invention is represented in the accompanying drawings, in which,

Figure 1 represents a front view of a chair embodying my invention, certain parts being shown in section and other parts broken away to show some of the fastening means.

Fig. 2 represents a vertical central section taken in the plane of the line A—A of Fig. 1, and also a vertical central section through 25 the arm upholstery and fastening means.

Fig. 3 represents a horizontal section through the arms and the back frame members showing the seat frame with the cover attaching means at the corners.

30 Fig. 4 represents an enlarged detail sectional view, showing the cover attaching and locking means.

Fig. 5 represents a view of a portion of the back of the chair, showing the fastening 35 means.

Fig. 6 represents an inverted plan view of a portion of the seat cover, showing one arrangement of the hook carrying strips.

Fig. 7 represents a similar view showing 40 another arrangement of the hook carrying strips, and

Fig. 8 represents an enlarged detailed sectional view of the front seat frame member, showing the cover fastening means.

45 The frame of the back of the chair is denoted by 1, and has the usual rabbet 2 in which the back of the chair rests. The legs of the chair are denoted by 3, the arms by 4, and the frame members of the seat by 5.

50 The back is made up of the plate 6, covered with the usual upholstery material, such as hair or the like, and with a suitable upholstering cloth 7, which is riveted to the edges of the plate 6, or sewed thereto, through holes provided for that purpose. The plate 6 is cut to fit into the rabbet 2

of the frame 1, and may be made of a thin sheet of metal or other suitable material. The plate 6 with its stuffing material and cover 7 forming the upholstered back of the 60 chair, is held in place by pins 8 which enter slots 9 in the frame 1, and pass through loops 10 in the plate 6, as shown in Figs. 1 and 5. The pins 8, which are sufficient in number to securely hold the back to the 65 frame have their ends 11 upturned to facilitate their insertion and removal.

The seat 12 of the chair is permanently attached thereto and is constructed in the usual manner with springs and hair or other 70 suitable filling material covered with a first sheet of strong cloth permanently fastened in any suitable manner to the tops of the seat frame members 5. A removable cover 13 for the seat 12, is cut in the form and 75 to the dimensions desired in order to completely cover the seat 12 and to fold down on to the horizontal frame members 5.

Attached to the edges of the cover 13, is a strip 14 which may be of any suitable material, such as sheet steel, to which strip is attached a number of hooks 15. To the seat frame members 5, at the corners adjacent the legs 3, are attached angle iron pieces 16 which are spaced a slight distance 85 from the frame members 5, in order to provide space for the insertion of the flat locking plates 17 between the seat members and the angle iron pieces 16. The locking plates 17 which have handles 18 to facilitate their 90 movement, are provided with a series of holes 19 adapted to register with similar holes 20 in the angle iron pieces 16.

Sockets 21 are located in the upper face of the rear and in the vertical exterior faces 95 of the side and front seat frame members 5. The sockets 21 are partially closed by means of a strip 22, securely fastened to the frame in any suitable manner.

The removable cover for the seat is placed 100 in position in the following manner:

When the angle iron pieces 16 and the locking plates 17 have been put in position so that the holes 19 and 20 register, the cover 13 is stretched over the seat 12 and the hooks 105 15 forced through the holes 19, 20. The locking plates 17 are then moved through the medium of the handles 18, until they assume the position illustrated in Fig. 4, in which position they lock the hooks 15 in the 110 holes 20 of the angle iron pieces and thus firmly secure the cover at its four corners.

The margins of the cover are then drawn down on to the seat frame members 5 until the hooks 15 pass the strips 22 and enter the sockets 21. The flexibility of the strip 14 5 will tend to keep the hooks in the sockets 21, after they are in place, but if it is desired to more firmly fasten the hooks in the sockets, locking plates, similar to locking plates 17, may be used.

10 If it is thought desirable, additional means for fastening the removable cover to the seat may be used. Fig. 7 shows attached to the cover 13, an additional strip 23, provided with hooks similar to hooks 15, which 15 are adapted to enter the sockets 24 on the horizontal faces of the side and front seat frame members 5, as shown in Fig. 3.

The removable upholstery for the arms 4, 20 consists of a sheet 25 of thin material, such as sheet steel, bent into U-shape and covered on the outer face with hair or other stuffing material and with the upholstering cloth 26. The cloth 26 is fastened to the sheet 25 by 25 riveting, sewing or in any convenient manner. Attached to the inside of the sheet 25, is a threaded pin 27 which passes through the hole 28 in the arm of the chair and coacts with a nut 29, countersunk in the bottom of the arm, to lock the upholstery to the arm.

30 It will be seen from the foregoing description that my invention obviates the use of bolts and screws such as were heretofore customarily employed in attaching upholstery, and it may be applied in connection 35 with articles of furniture having upholstery of various kinds, such as velour, silk, leather, etc. without danger of injuring or marring the furniture or the upholstering material used. The upholstery may be made separately and in many sets of different materials, so that the furniture dealer will have in stock a collection of various kinds of upholstery for the same article of furniture and can apply to the furniture the particular 40 kind of upholstery desired by the purchaser. Since the removable upholstery which is the subject-matter of this application is not cumbersome and can very easily be protected from light and dust, the dealer

can carry a large assortment for the purchaser to select from, and he will not be obliged to carry in stock a large amount of furniture having permanent upholstery which will fade and become shop worn awaiting sale. Furthermore, the owner of 55 furniture embodying my invention can at any time he desires, remove the upholstery from his furniture and replace it by other upholstery in a very short time and at comparatively small expense.

60 It is evident that various changes might be resorted to in the construction, form and arrangement of the various parts without departing from the spirit and scope of my invention, and hence I do not wish to limit myself strictly to the structure herein shown and described, but

What I claim is:

1. An article of furniture having a frame provided with legs, a seat, a removable cover 70 for said seat, a series of sockets in said frame, corner pieces, adjacent the legs, attached to the frame and spaced therefrom, a series of holes in the corner pieces and a series of hooks carried by said cover and 75 adapted to enter the holes in the corner pieces and the sockets in the frame to fasten the cover to the frame.

2. An article of furniture having a frame provided with legs, a seat, a removable cover 80 for said seat, a series of sockets in said frame, corner pieces, adjacent the legs, attached to the frame and spaced therefrom, a series of holes in the corner pieces, a series 85 of hooks carried by said cover and adapted to enter the holes in the corner pieces and the sockets in the frame to fasten the cover to the frame, and sliding means interposed between said corner pieces and the frame to prevent the removal of said hooks.

90 In testimony that I claim the foregoing as my invention, I have signed my name this 25th day of January, 1917.

LOUIS COURTIAT.
